UNITED STATES PATENT OFFICE

AMY BURKETT, OF ST. GEORGE, NEW YORK

LINGERIE STRAP HOLDER

Application filed July 31, 1931. Serial No. 554,350.

This invention relates to a clasp to be used as a holder for lingerie straps and one object of the invention is to provide a clasp which may be sewed against the inner face of a shoulder seam of a dress where it will be firmly held in its proper position and to further so construct the clasp that when it is sewed to a dress, a lingerie strap may be very easily engaged with the clasp or released therefrom, but will not be liable to accidentally slip out of engagement with the clasp.

Another object of the invention is to provide a clasp of this character having upper and lower jaws, the upper one of which is so formed that it will permit a lingerie strap to be guided into and out of place between the jaws and to so form the free end portion of the lower jaw that it will assist to guide a lingerie strap into place between the jaws.

Another object of the invention is to so form the free end portion of the lower jaw that it will extend upwardly when the clasp is sewed to the shoulder seam of a dress and not be liable to press into a person's shoulder and cause the clasp to be uncomfortable when worn.

Another object of the invention is to provide a clasp of this character which may be formed either from a strip of resilient sheet metal or from a strand of resilient wire.

The invention is illustrated in the accompanying drawings wherein:

Figure 1 is a perspective view showing a clasp of the improved construction sewed to the shoulder portion of a dress shown torn away and lingerie strap engaged with the clasp.

Figure 2 is a perspective view of a clasp of the improved construction formed from a strip of resilient sheet metal, and

Figure 3 is a perspective view showing the improved clasp formed of a strand of resilient wire.

This improved clasp is to serve as a lingerie strap holder and in Figure 1 has been shown applied to the shoulder portion of a dress.

This clasp which is indicated in general by the numeral 1 extends longitudinally of the shoulder seam of a dress and is secured

against the inner face of the shoulder seam by stitches 2 which are passed through the clasp and shoulder portion of the dress. The clasp has upper and lower jaws as shown in Figures 2 and 3, the free ends of which extend inwardly from a person's shoulder and a lingerie strap 3 is to be moved between the jaws into place as shown in Figure 1. When the strap is so engaged with the clasp it will be firmly held in place and prevented from slipping out of its proper position. The clasp may be formed either from a strip of resilient sheet metal as shown in Figure 2 or from a strand of resilient wire as shown in Figure 3.

When the clasp is formed of sheet metal, the strip of resilient metal is bent intermediate its length to form upper and lower jaws 4 and 5 joined by a U-shaped bridge portion 6 which serves to integrally connect the two jaws and also serves as a spring and yieldably resists movement of the free ends of the jaws away from each other. Openings 7 are formed through the upper jaw in spaced relation to each other longitudinally thereof to receive the stitches 2 by means of which the clasp is to be secured to the shoulder portion of a dress.

At its free end the upper jaw is rolled as shown at 8 thereby forming a cylindrical terminal for the jaw which serves as a closure for the outer end of space between the jaws and also serves to guide a lingerie strap into and out of position between the jaws. It should be noted, however, that this cylindrical end portion will very effectively prevent the lingerie strap from accidentally slipping out of place when it is engaged by the clasp.

The lower jaw projects beyond the rolled end of the upper jaw and has its free end portion curved upwardly as shown at 9. Therefore a lingerie strap may be moved into position to rest upon the projecting end portion of the lower jaw and then slid inwardly between the lower jaw and the rolled end of the upper jaw into place between the jaws. In view of the fact that the extreme end of the lower jaw is curved upwardly and is formed with a rounded edge, it will be prevented

from pressing into a person's shoulder and causing the clasp to be uncomfortable when worn.

The strand of resilient wire from which the clasp shown in Figure 3 is formed is doubled intermediate its length to form a lower jaw 10 which has spaced side arms 11 joined by a bridge 12 which is curved upwardly and takes the place of the lip 9. After the strand has been bent to form the lower jaw, the arms of the strand are then bent upwardly as shown at 13 and back in overlying spaced relation to the lower jaw to form an upper jaw 14 corresponding to the jaw 4 and connected with the lower jaw by a U-shaped bridge portion corresponding to the bridge 6. Each side arm 15 of the upper jaw is crimped to form eyes 16 extending transversely of the jaw in spaced relation to each other longitudinally thereof and these eyes take the place of the openings 7 and are intended to be engaged by a thread when the clasp is sewed to the shoulder portion of a dress. The ends of the strand are bent inwardly and upwardly to form loops 17 which rest upon the side arms of the lower jaw and take the place of the rolled end 8 of the jaw 4 and serve to guide a lingerie strap into and out of position between the two jaws and prevent the strap from slipping out of place.

It will thus be seen that the clasp may be formed either of a strip of resilient sheet metal or a strand of resilient wire and in either case the clasp will have upper and lower jaws integrally united by a U-shaped bridge portion, one having a rolled free end which bears against the other jaw in spaced relation to its free end.

What is claimed is:

1. A lingerie strap holder comprising a clasp having upper and lower leaves united at one end of the clasp by a bridge constituting a spring element yieldably resisting movement of the leaves away from each other; the upper leaf having its free end rolled downwardly and inwardly to form a closure for space between the leaves and bearing against the lower leaf, the lower leaf having its free end portion projecting beyond the rolled end of the upper leaf and curved upwardly.

2. A lingerie strap holder comprising a clasp having upper and lower leaves united at one end of the clasp by a bridge constituting a spring element yieldably resisting movement of the leaves away from each other, the upper leaf being provided with thread receiving passages whereby the clasp may be disposed against the inner surface of a shoulder seam of a garment longitudinally thereof and sewed firmly into place, the free end of the upper leaf being rolled downwardly and inwardly to form a closure for space between the leaves and bearing against the lower leaf, the lower leaf having its free end portion pro-

jecting beyond the rolled end of the upper leaf and curved upwardly.

3. A lingerie strap holder comprising a clasp formed from a strip of resilient sheet metal bent intermediate its length to form upper and lower leaves joined at one end by a U-shaped bridge, the upper leaf being formed with thread receiving openings and having its free end portion rolled downwardly and inwardly to form a sleeve closing the outer end of space between the leaves and serving to guide a lingerie strap into and out of place between the leaves, the lower leaf having its free end portion projecting beyond the rolled end of the upper leaf and curved upwardly.

4. A lingerie strap holder comprising a clasp formed from a strand of resilient wire bent intermediate its length to form a lower leaf having spaced side arms and then bent upwardly and forwardly to form an upper leaf having side arms connected by U-shaped bridge portions to rear ends of side arms of the lower leaf, the side arms of the upper leaf being crimped intermediate their ends to form thread receiving eyes extending transversely of the upper leaf, free ends of the side arms of the upper leaf being curved downwardly and inwardly and then upwardly to form loops bearing against side arms of the lower leaf and serving to close space between front ends of the leaves and guide a lingerie strap into and out of place between the leaves.

In testimony whereof I affix my signature.

AMY BURKETT.
